CLAIM

(22) Filed: **May 28, 2002**

The ornamental design for a face for a carrier for a portable computer drive, as shown and described.

Related U.S. Application Data

DESCRIPTION

(62) Division of application No. 29/143,830, filed on Jun. 21, 2001, now Pat. No. Des. 461,815.

FIG. 1 is a front elevational view of a face for a carrier for a portable computer drive showing my new design; FIG. 2 is a rear elevational view thereof;

(51) **LOC (7) Cl.** **14-02**

FIG. 3 is a right side elevational view thereof wherein the broken lines used to show the remainder of a carrier for a portable computer drive are shown for illustrative purposes only and form no part of the claimed design; FIG. 4 is a top plan view thereof;

(52) **U.S. Cl.** **D14/444**

FIG. 5 is a bottom plan view thereof; and, FIG. 6 is a left side elevational view thereof.
